ANDREW M. EASTMAN, OF MILFORD, AND JOHN R. THOMAS, OF BOSTON,
MASSACHUSETTS, ASSIGNORS TO THE S. A. WOODS MACHINE COMPANY,
OF MASSACHUSETTS.

CUTTING-OFF SAW.

SPECIFICATION forming part of Letters Patent No. 371,676, dated October 18, 1887.

Application filed December 18, 1886. Serial No. 221,913. (No model.)

To all whom it may concern:

Be it known that we, ANDREW M. EASTMAN, of Milford, in the county of Worcester and State of Massachusetts, and JOHN R. THOMAS, of Boston, in the county of Suffolk and State of Massachusetts, have invented a certain new and useful Improvement in Cutting-Off Saws, of which the following is a specification.

Our improvement relates to swinging saws for cutting off timber, lumber, &c.; and it consists in certain new and improved constructions and combinations of the same, substantially as hereinafter described and claimed.

In the drawings, Figure 1 is a side elevation of a saw-bench provided with a cutting-off saw and our improvements relating thereto. Fig. 2 is a top plan view of the same with the saw-table partly broken away to show the construction of the working parts. Fig. 3 is an end view of the same. Fig. 4 is an enlarged view of a portion of the opposite side of the machine from that shown in Fig. 1. Fig. 5 is an end view of Fig. 4, partly in section on line *a a*, showing details of construction.

25 A is the frame of the machine, which is of a rectangular form, as usual, and has the table A' placed horizontally on top of it. This table receives the lumber to be cut off.

S is the saw, which is attached as shown, 30 mounted upon the outer ends of the arms s s in boxes. These arms are pivoted at their lower ends to the ends of another pair of arms, s' s'. The arms s' s' are in turn pivoted upon the shaft or axle b, supported in boxes on the 35 side rails of frame A, as shown in the drawings. The boxes at the outer ends of the arms s s have attached to them guide-pieces c on each side, which fit on ways c' and slide back and forth thereon horizontally, allowing the 40 saw to be traversed forward to the position shown by dotted lines in Fig. 1 and drawn back again at will.

In order to drive the saw while being moved back and forth in the operation of cutting off 45 the lumber, a pulley, p, is attached to its shaft between the boxes, and another pulley, p', is attached to the pivot or shaft which joins the arms s s and s' s' together, so as to revolve thereon. A larger pulley, B, is attached to

the central portion of the shaft b, and a tight 50 and loose pulley, B' B'', is attached to the outer end of the same shaft, and receives its motion by a belt from any suitable counter-shaft. Upon the upper sides of the arms s' s' are attached ears s² s², and pivoted to these ears are 55 arms s³ s³, extending toward the arms s. The other ends of the arms s³ are connected by a shaft, upon which is mounted loosely the pulley p². Another shaft rigidly fixed in the arms s³ s³ and extending transversely across 60 the machine between them carries upon it the bracket d, which supports the weight d' on the top of the bracket, which is in the form of a bar parallel to the arms s³. By sliding this weight d' along on the bracket 65 toward the ears s² or away from them it will diminish or increase its pressure upon the outer ends of those arms and the pulley p² as desired. The weight is held upon the bracket in the desired position by a set-screw. A belt, 70 e, is carried around the driving-pulley B underneath the idler-pulley p², over the pulley p of the saw-shaft, around and underneath the pulley p' at the junction of the arms, and back to pulley B. The tension of the pulley p² upon 75 this belt keeps it taut, no matter what the position of the saw may be in sliding back and forth upon the ways c', and thus enables the saw to be driven by the belt e with the same tension at all parts of its traverse. 80

Our improvement in this mechanism consists in attaching the idler-pulley p² to the arms s³, pivoted upon the arms s' and extending horizontally over the same, as shown, thus enabling us to apply the weight d' to these 85 arms s³ and increasing or diminishing the tension of the idler-pulley p² upon the belt at pleasure.

In cutting off extremely large or hard timber it is frequently desirable to have the saw 90 moved forward to the position shown in dotted lines by the power of the driving machinery, and it is also desirable to be able to stop the forward movement of the saw at any desired point and allow it to retire, thus making a 95 partial cut of any desired depth in the timber.

To draw back the saw to the position shown in Fig. 1, a strap, c², is attached to a cross-bar

connecting the sliding pieces c , and this strap is carried around the drum c^3 and has its other end made fast thereto. The shaft of the drum c^3 extends transversely across the frame and is 5 mounted in bearings thereon, as shown, and has the gear-wheel c^4 attached to one end of it. This gear-wheel meshes with the gear c^5 , attached to the drum c^6 , around which a cord is wound and attached thereto at one end, and a 10 weight, c^7 , is attached to the other end of such cord. As the gear-wheel c^4 is smaller than its drum c^3 and smaller than the gear-wheel c^5 , the movement of the weight up and down in drawing the saw back is much less in distance than 15 the movement of the saw, and all necessity of having the weight pass through the floor on which the machine rests is thereby obviated.

For drawing the saw forward in cutting off timber the following mechanism is employed:

20 Upon the opposite end of the shaft b from the tight and loose pulleys is attached a pulley, B^4 , in line with a pulley, B^3 , which is upon the outer end of the shaft b^7 . The latter is mounted in bearings in the frame of the machine and 25 extends transversely across it. A drum, d^2 , is mounted loosely upon this shaft and has a flange, d^3 , attached thereto. A strap, d^4 , extends from one of the arms s around this drum and is made fast thereto. A corresponding flange, d^5 , to that lettered d^3 is made 30 fast to shaft b^7 , these flanges being face to face. A collar, d^6 , is mounted loosely upon shaft b^7 , having one face bearing against the drum d^2 and a projecting portion or hub, d^7 , attached to 35 the other end of it, which is flattened on two sides. The face of the collar d^6 , where the hub d^7 joins it, is inclined to its axis, and a wedge, d^8 , is made to enter between this face and the frame A of the machine, and receive 40 in a slot within it the hub d^7 , so as to prevent the latter and the collar d^6 from revolving with the shaft. A link, d^9 , is attached to the lower end of this wedge by a pivot, and a treadle, d^{10} , is attached to the lower end of this link, by a 45 pivot, d^{11} . This treadle is in suitable position for the foot of the operator, and by pressing upon it the link d^9 and wedge d^8 are lifted, and the collar d^6 is compressed against the drum d^2 , closing the flanges d^3 d^5 firmly together and causing 50 the drum d^2 to revolve with the shaft b^7 . This draws upon the strap d^4 and carries the saw forward. By releasing the treadle d^{10} at any time in the forward movement of the saw the latter will be instantly released and drawn 55 back by the weight c^7 .

What we claim as new and of our invention is—

1. The combination of the jointed arms s s' ,

pivoted to the frame and to each other, the saw S , mounted upon the free end of arms s and s' , provided with a driving pulley, p , the pulley p' , mounted on the pivot connecting arms s s' , the pulley B , mounted on the shaft b , and the arms s^3 , pivoted to the arms s' , extending horizontally toward the junction of the latter with arms s , and carrying at their outer ends the pulley p^2 and weight d^7 , substantially as described.

2. The combination of the frame A , provided with guideways c' , the saw S , mounted upon guides c , moving on said guideways, the shaft b^7 , and the drum d^2 , arranged to turn loosely, provided with strap d^4 , connecting it to said guides and saw and clutch mechanism provided with a foot-pedal and adapted to clutch said drum 75 to said shaft and release the same therefrom at any desired point in the winding of said strap upon said drum, substantially as described.

3. The combination of the frame A , provided with guideways c' , the saw S , mounted upon guides c , moving on said guideways, the shaft b^7 , the drum d^2 , arranged to turn loosely, provided with strap d^4 , connecting it to said guides and saw, and clutch mechanism adapted to clutch said drum to said shaft and release the 85 same therefrom at any desired point in the winding of said strap upon said drum, and the strap c^2 , drum c^6 , and weight c^7 , connected therewith, adapted to withdraw said saw when so released, substantially as described.

4. The combination of the frame A , provided with guideways, the saw S , mounted upon guides thereon, the shaft b^7 , mounted in said frame, the drum d^2 , provided with strap d^4 , connected to said saw-guides, the collar d^6 , attached 95 to said shaft on one side of said drum, and the collar d^6 and wedge d^8 , embracing said shaft and adapted to clutch said drum and collar d^6 together, substantially as described.

5. The combination of frame A , provided with guideways, the saw S , mounted on guides thereon, the drum c^3 , provided with strap c^2 , connected to said guides, and the drum c^6 and its weight c^7 , connected by a strap or cord therewith, said drum c^6 being connected to 105 drum c^3 by gearing adapted to cause said strap c^2 to be wound and unwound thereon more rapidly than the strap of weight c^7 is wound upon its drum, and said drum c^6 and its gear c^5 being located below the bed of the machine, substantially as described.
